(54) **LEAD, WHITE**

(76) Inventor: **Edward Clark**

Edward Clark

The Schedule referred to in these Letters Patent, and now being part of the same, containing a description in the words of the said Edward Clark himself of his improvement in the manufacture of metallic salts, usually denominated White or carbonate of Lead, carbonate of copper, acetate of Lead, acetate of copper, & the acetate or pic acetate of iron, for which Letters Patent were granted, dated the 11th day of December 1838, which Letters Patent were cancelled on account of a defective specification of them, Letters Patent granted on the 3d day of July, 1839, which last, Letters Patent are hereby cancelled, also on account of a defective specification.

To all whom these Presents shall come:

Whereas it is known that E. Edward Clark, of the town of Lancaster in the State of New York, is a citizen of the United States, have invented and improved a new and useful improvement in the manufacture of the carbonate of Lead, or White Lead, or if the operation succeeds so as to apply the process in the manufacture of the acetate of Lead, the carbonate & acetate of copper and acetate & pic acetate of iron — The process will produce all the above results by merely varying the molar report to be acted upon, & by increasing the dilute proportions of the acetate acid or vinegar when the manufacture of the acetates are required, & stopping emitting the carbonic acid where the acetate or pic acetate of iron is intended to be produced. But the process is principally used in the manufacture of white lead, a carbonate of lead, & to that effect in the manufacture of the sugar or acetate of lead. I will now describe myself in this description — This being an unpatented operation for a Patent to be issued in due time and in due proportion deserved.

To carry into effect my improvement in the manufacture of white lead, I construct a cylindrical vessel of brick, the dimensions perfectly height & about the said six feet high. This vessel

should be made lighter & stronger enough to resist some pressure from within. This is called the bore-tube, chambered or otherwise. It may also be made in the form of a box base or platform, being lighter & stronger, higher & lower or lighter & higher, or of any other convenient shape or size. & the pieces & quantity of metal to be used intended to be operated upon at a time may require. The sheets of lead cast in the usual manner 8" from, and being supported on wooden rods or bats which are supported by bats secured to the inside of the bore-tube, chambered, & the sheets are placed as closely as they can conveniently be, & not touch each other. The sheets of lead may be rolled & placed on shelves prepared with poles, or upon any kind of bats or bats, which are in such a certainty, arranged, bats not in contact with it, or in any other manner so as to expose their surface to the action of the said agents & other agents brought to act on them.

The agents I use to carry the plastic lead & make the said lead called sulphate of lead or white lead, are the sap of sassafras, salicin & root gum & any other gallic bark of which is contained in sufficient quantity in the atmosphere & these agents are made much more effective by being melted & used in greater quantities & properties than they have heretofore been applied to the same purpose, in the same form of lead, & by means of all which of practice is made & accepted results.

To avoid the impure of being used to as to fit the covering & certain & to envelop the rods of lead with it in the most effectual manner in my object, & this I accomplish in various ways, without being able to give a detailed process to follow.

Firstly, I put the sassafras into a capped stile, as shown at C fig 1. of the annexed drawing, & then by applying sheets to the surface below, prevent the sap of sassafras, which passes from the stile into the pipe, & thence along with the other agents the live branch pipe, & the & the stop cock C. & so into

the corroding chamber A, & the same also in fig. 1. When this method is resorted to, the corroding agents pass from the burnt pipe B, & into the long box of three or four inches by three & a half inches, which are placed on the sides of the chamber, & are perforated in their sides with a number of small holes for the more equal distribution of the corroding agents.

Secondly, when vinegar or any other acid is placed in the bottom of the corroding chamber, and this which is placed in a beaten pipe which communicates with the vinegar generator, shown at 7, & 8, & 9, are passed over a mere heat over the bottom of the vinegar according to the quantity of heat required, to corrode the metal acids are the most efficient measured.

Finally, if put vinegar in vessels, 8 & 10 as shown, above it, & place rods of sheet lead, 8' passing through them, & with these rods, introduce the carburet, and just atmospheric air heated to such a temperature as to produce the required evaporation of the vinegar — or finally, if placed a stick on the outside of the corroding chamber, which is furnished with a stirring, discharging, & vapour pipe, each furnished by a stop cock. One of these pipes for the admission of water into the box, and is to turn right off & the other is to conduct the steam from it, & communicate the opposite end of, back to the corroding chamber, for the evaporation of the vinegar. This pipe is conducted thro' a tube or packing box with the corroding chamber, & out again, which contains the vinegar, is infolded in cloth & passed & is there, from a convenient part of the corroding chamber, taken out thro' a hole in packing. And the pipe should be furnished with stop cocks to regulate the supply of water & steam passing thro' them. Some small cocks or other contrivances are used to ascertain the depth or quantity of vinegar which the length of the stick, in chamber may contain. The quantity of carburet acid gas necessarily to be introduced into the corroding chamber is not great. A few feet is used for

heating) the vineyard, I take this gas by means of the induction pipe to the blowing apparatus, from the furnace of the boiler or stove, where coal is not used. I take it, from a small furnace built for the purpose, in which sulphuric coal or wood is burned properly, for the generation of this gas. A view of this pipe is shown at 3, fig. 1, and a sectional view at 3, fig. 3, the former Drawing. The quantity of sulphuric acid in oxygen gas which is contained in it, is more considerable than that of the carburee gas (say in the proportion of two to one), and I obtain this after the branch pipes and apertures in the pipe at 3, shown at 3, fig. 1, and at 3, fig. 3, are passed over apertures at or near the top of the furnace, which I leave for the purpose. The introduction of an excess of the carburee agents, into the incinerating chamber, is of no material consequence, because they pass off there. The branch pipes shown at 2, & 2, in the pipe 3, and those just the other chamber successively make them perfectly, or quite separated.

Connected with the requisite supply of oxygen gas, is an incinerating apparatus, which leads gas into the incinerating chamber (a gas blowing apparatus, which receives the gas above named in the manner before described to force them into the incinerating chamber). Instead of this, the carburee acid gas (the vapor of vinegar may be furnished) within the incinerating chamber. For the purpose of introducing these gases into the incinerating chamber, I have made use of the incinerating apparatus (shown 3, by striking its front), so that one portion of the atomosphere (air) was caused to pass into a light furnace, containing ignited coal & thus furnish the carburee acid gas, while the other supplied the requisite quantity of oxygen gas. I have also used the vapor bellows which is constructed by placing two inverted vessels into another, containing water & furnished with induction & induction valves in the pipe, which were made to feed the requisite supply of

the above-mentioned part of the chamber, by giving it the inverted position, a side-burner constructed like an up-and-down heater, and its side-hand adjustable side-burner for this and purpose.

Description of both of these latter will be found in my other works treating on Hydromel. But, there are a vast number of side-burners, which are not so easily made, being either short, or long, or wide, or narrow, or of various sizes in the boiler. It has, however, found sufficient to twenty minutes in a minute, for a large sufficient quantity of the gas to set up in about fifty or sixty feet of tubing, after which leads to the same time.

The fig. 1. the gas, & vapors of vinegar are represented as being forced, in a mixed or combined state into the gas-distributing box of the preceding chamber. This box is numbered 2. fig. 2.

It is, especially as it is in contact, to which the gas is introduced, through the gas-distributing box by the tubes which the heat is impressed on the medium of steam, using the pipe A.B. & B.C. pipes C.D. to & through the trough containing vinegar which lies on the floor of the corralling chamber, affords the requisite quantity of heat required, & degree of temperature.

The vinegar bath or trough with its steam pipe & stop-cock are shown at A.B. & C. fig. 2. It should be remarked that, in proportion to the increase of temperature with the process of vinegar to a certain extent be expedited; however the temperature should range somewhat between 100° & 120° of Fahrenheit; & the operator should regulate it, by the manner & as appears in the last article and the chamber. The first should be increased by the gas increased when the bath is too much & heat increased the heat is too high. Ordinarily, the gas when combined with the vapors of vinegar, will supply the requisite heat, without being introduced by themselves.

I pass then through apartment 1) which contains the heat, such as that represented at A.B. fig. 2; which is heated by the smoke pipe A.C. passing from the furnace to this above the chimney. — The making the solution of sugar of tartar.

the acetate of copper, it is only necessary, when the acid coppered
beam corroded, to shut off the gas (increasing the water vapor)
until the carbonates which have been previously formed are
converted into acetates & then evaporating the liquid which
remains in the corroding chamber.

In making the acid acetate or acetate of lead the vapor
of vinegar and atmospheric air only are admitted & the quantity
of the latter must be particularly regarded, with the acid often
left in solution by the acid will be precipitated. When formed
this material should be put into zinc cases, 6 to 8 ft.
long required for use.

The carbonate of copper is made in precisely the same way
as the carbonate of lead, but its conversion from the metallic
state being much more slow & difficult, than that of lead;
it is more expedient to conduct this process by applying the
quickly expanded residue of the last corroding chamber to it.

When the corroding agents are so abundantly supplied as
to place a free circulating shot of the gas distributed around the
fig. 7. but containing about half the number of holes in the
inside and upper part of the corroding chamber & connect
it by the branch pipe B to the pipe & pipe which leads to
a discharge itself into one adjacent chamber in succession which
is supplied with shot lead or copper, with a pipe; of course
the residue of the corroding agents should gradually escape
the first application. The blowing cylinder is provided below
it to the cylinder of a steam engine with the valves, which
may be put into operation by water, steam, or
natural power.

This improvement consists in applying the com-
bined process before described to all other substances, the
same which may be arranged for giving oxygen gas &
nitrogen gas, either separately or in a state of combination
with other substances into chambers or vessels heated or not.

heated which have previously been impregnated with vinegar, in sheets of lead or copper according to the metal designed to be acted on. It therefore claims his improved invention that the pipe of foregoings atmosphere be introduced into close contact, & thereby (consequently) chambers and connected with carbureted acid gas to the vapour of vinegar & increasing the acid action by adding heat, pursued by means by which the corroding agents are first put into close contact with the sheets of lead or copper, and are made to act more vigorously than in any other way heretofore known & practised - all in connection with each other, & with the above described corroding chambers, vats, tanks, boxes, barrels, & apparatus for conducting & forcing the agents for corroding the lead or copper, into the corroding chambers in the manner above described & in any other manner substantially the same. (See accompanying Drawing) which further illustrates my specification.

Description of the several drawings - Fig. 1. represents a pair of corroding vessels with a blowing apparatus, for supplying them with atmosphere acid carbureted acid gas, & the vapour of vinegar. It is so arranged that corroding vessels or chambers. 2. the blowing apparatus is apparatus of the kind in copper barrel containing vinegar. 3. the furnace for heating the vinegar & air for supplying carbureted acid gas to the furnace pipe for supplying the blowing apparatus with carbureted acid gas from the furnace. It has apertures to admit a supply of atmosphere air into the foregoings cylinder like the pipe 3. If the cylinder pipe for conducting the carbureted acid gas, the atmosphere air, & the vapour of vinegar into

the corroding cisterns or chambers. A. B. C. the lateral branch pipes for supplying the distributing boxes round the B. B. fig. II, with the corroding materials from the A. A. pipe fig.

C. D. E. the stop cocks to regulate the admission or exclusion of the corroding materials at the pleasure of the attendant. H. H. K. the cistern branch pipes with their cocks. L. the mixed cistern pipe.

Fig. II, represents an interior view of the corroding cisterns or chambers, partially supplied with their castings of cast-iron, disposed for corrosion in various ways. A. A. represents two chambers back of the B. B. the boxes perforated with small holes for distributing the corroding materials in the chambers. C. D. E. E. sheets of iron suspended or riveted as support for corrosion.

Fig. III represents a sectional view of the burning apparatus, furnished to H. H. K. as shown cut in fig. I.

Fig. IV. representing a view of corroding cisterns with the gas distributing apparatus as described in Fig. I. with an additional apparatus for heating the gases & also for generating the heat steam within the chambers. A. B. C. A view of the chambers or corroding cisterns. B. The burning cylinder. C. The steam boiler. D. The furnace. E. E. E. main steam pipe. F. G. H. branch steam pipes leading from B through the troughs G, in the chambers. G. G. H. the ends of the troughs as shown projecting from the corroding cisterns in A. Fig. V. for receiving the vapor which is to be heated by the steam pipe & then the apparatus there shown at y.

H. H. K. the pipes for conveying the gases thru' the heating chambers of the furnace as shown at C. C. fig. VIII from the burning cylinder, thru' the branch pipes K. K. to the corroding chambers. J. K. L. the lateral branches of the main gas pipe for conveying the gas to the distributing pipes as shown at C. C. fig. I. & furnished with stop cocks the same

as shown in the staved pipe. At the smoke pipe, Fig. V. Two of the chambers open to receive A. A. the two chambers of the (conducing) cylinder B. B. troughs for containing various boxes for distributing the gases. D. D. rods or bats for supporting the sheets of lead C. C. the sheets of lead suspended over the troughs.

Fig. VI. A vertical section of one of the chambers with its door removed. A. A. are the rods or bats for supporting the sheets of lead. B. the trough for containing the various boxes and distributing box.

Fig. VII. A general view of one of the cylinders with its trough, box & pipe. At the trough for containing various boxes, the staved pipe running through the ringed trough A. & the pipe for conveying off the waste steam or condensed vapors D. D. stop cocks for regulating the supply of the conducting material. E. the gas distributing box & the branch of the main pipe connected with the distributing box.

Fig. VIII. A sectional view of the blowing cylinder, C. chamber, for heating the gases. A. represents the piston head & rod of the cylinder. B. B. the induction valves. C. the induction valves. D. the induction pipe for supplying carbonic acid gas from the furnace and from the sputtered stone and E. the sputtered for admitting atmospheric air. At the induction pipe which conveys the gas from the blowing cylinder to the heated chamber. F. F. G. holes for admitting water into them for heating the ringed troughs. H. H. the furnace. I. I. the smoke pipe. K. K. the chamber for heating the gases in their passage thru the pipes I. to be distributed thru the various A. pipe leading from the heated C. C. chamber for the conveyance of the heated gases as above. (Appn. described.
